(57) **CLAIM**

The ornamental design for a base for astronaut starry sky projector, as shown and described.

DESCRIPTION

FIG. 1 is a front elevation view of a base for astronaut starry sky projector, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front and top perspective view thereof;

FIG. 8 is a rear and bottom perspective view thereof; and, FIG. 9 is another perspective view thereof, shown in a position of use.

The two foot holds and features within the adjacent crater, shown on the top of the article in FIGS. 5, 7 and 9, and the four circular features shown on the bottom of the article in FIGS. 6 and 8, illustrated in light grey, depict portions of the base for astronaut starry sky projector that form no part of the claimed design. The astronaut figure illustrated in light grey in FIG. 9 depicts environmental structure and forms no part of the claimed design.
